UNITED STATES PATENT OFFICE

125,046

DESIGN FOR A COMBINATION MEDICINE APPLICATOR AND DROPPER

Edward William Ballentine, Toledo, Ohio

Application October 20, 1939, Serial No. 87,777

Term of patent 14 years

To all whom it may concern:

Be it known that I, Edward William Ballentine, a citizen of the United States, residing in Toledo, in the county of Lucas and State of Ohio, have invented a new, original, and ornamental Design for a Combination Medicine Applicator and Dropper, of which the following is a specification, reference being had to the accompanying drawing, forming part thereof, in which:

Figure 1 is a perspective view of a combination medicine applicator and dropper, showing my new design; and

I claim:

The ornamental design for a combination medicine applicator and dropper, as shown.

EDWARD WILLIAM BALLENTINE.
